M. M. ADLER

DETONATING TOY

Filed Nov. 3, 1925.

INVENTOR:
Milton M. Adler
BY
Fraenkel and Richards,
ATTORNEYS.

Patented May 4, 1926.

UNITED STATES PATENT OFFICE.

MILTON M. ADLER, OF NEWARK, NEW JERSEY.

DETONATING TOY.

Application filed November 3, 1925. Serial No. 66,471.

To all whom it may concern:

Be it known that I, MILTON M. ADLER, a citizen of the United States, residing at Newark, in the county of Essex and State of New Jersey, have invented certain new and useful Improvements in Detonating Toys; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in detonating toys; and the present invention has reference, more particularly, to a novel toy, in the form of a cane, or the like, provided at its striking end with an improved and simply constructed percussion or paper-cap receiving anvil, with a view of simplifying the construction of the anvil, and thereby greatly reducing the cost of manufacture, and still providing a perfectly harmless toy to be employed for the explosion of percussion or paper-caps, suitable for children of all ages.

The present invention, therefore, has for its principal object to provide a novel construction of parts comprising the toy, to be hereinafter more fully described, which shall be very simple and operative, and in which the objectionable features heretofore existing in devices of this character are fully overcome.

Other objects of the present invention not at this time more particularly enumerated will be clearly understood from the following description of the same.

The invention consists, primarily, in the novel detonating toy hereinafter set forth; and, the said invention consists, furthermore, in the novel arrangements and combinations of the several devices and parts, as well as in the details of the construction of the said parts, all of which will be more fully described in the following specification, and then finally embodied in the clauses of the claims, which are appended to, and which form an essential part of the said specification.

The invention is illustrated in the accompanying drawings, in which:

Figure 1 is a side edge view, and Figure 2

a front face view of a detonating toy made according to and embodying the principles of the present invention.

Figure 3 is a horizontal section through the anvil of the device, said section being taken on line 3—3 in Figure 1, looking in the direction of the arrow; Figure 4 is a transverse vertical section, taken on line 4—4 in Figure 2; and Figure 5 is a similar section, taken on line 5—5 in Figure 1.

Figure 6 is a horizontal section, similar to Figure 3; and Figure 7 a vertical section, similar to Figure 4, of a slightly modified construction of anvil.

Similar characters of reference are employed in all of the said above described views, to indicate corresponding parts.

Referring now to the several figures of the drawings, the reference-character 1 indicates one form of complete detonating toy, the same in this case comprising a stick or rod 2, one end of which is provided with a knob 3, or other suitable grasping means. The other end of the stick or rod is provided with a percussion or paper-cap receiving anvil 4, which as will be seen from an inspection of Figures 1 to 5 inclusive, consists of a pair of metal members 5 and 6, which are respectively made with suitably shaped open portions, as 7 and 8. Above and below these open portions, the said members 5 and 6 are respectively formed with longitudinally extending channels 9 and 10, and 11 and 12, all arranged when the members 5 and 6 are placed opposite each other, and secured together by means of a rivet 13, or the like, to provide a receiving socket for the arrangement therein, of the end-portion 14 of the stick or rod 2, and also to provide a guiding duct in which is movably disposed a pin or stud 15 formed with an enlargement or head, as 16.

The said members 5 and 6 are also preferably provided in their channelled portions 9 and 11 with inwardly projecting and pointed gripping projections, as 17 and 18, which are forced into the opposite sides of the portion 14 of the stick or rod, when the several parts are permanently secured in their assembled relation by means of the previously mentioned rivet 13, in the manner indicated in the several figures of the drawings. In its lower portion, the anvil-member 5 may also be provided upon its inner flat face with

suitably located retaining lugs or projections 19, adapted to be brought into registration with correspondingly located receiving depressions 20 in the inner flat face of 5 the other anvil-member 6, as will be evident from an inspection of Figure 1 of the drawings. From Figures 3 and 4 it will be seen, that one of the anvil-members as 5, is formed with an inwardly projecting portion 10 21, the end-portion of which is fitted in a recess 22 in the member 6, all arranged to provide a suitable strike-plate, against which the enlargement or head 16 of the pin or stud 15 is brought into forcible contact for 15 exploding or firing purposes, in the manner to be presently described.

In lieu of this form of strike-plate, the anvil-members 5 and 6 may be respectively provided with inwardly extending abutting portions, as 23 and 24, to provide a strike-plate of the construction illustrated in Figures 6 and 7 of the drawings.

This latter construction is somewhat preferable over the construction illustrated in 25 Figures 1 to 5 inclusive, since in the construction of anvil represented in Figures 6 and 7, both anvil-members are alike, so that both members can be cast from the same pattern; or may be struck up from the same die, and may be used either right or left, thus 30 facilitating the assembling operation of the parts, as will be clearly evident.

In using the device for firing or exploding a percussion or paper-cap, the latter is inserted into an open portion of either of the members 5 and 6, and placed directly upon the enlargement or head 16 of the pin or stud 15. The stick or rod 2 being held by means of its knob 3 in a raised position is 35 then moved with force in a downward direction, bringing the projecting end of the pin or stud 15 with force upon the ground, or against a stone, or the like. The result is that at the time of contact, the pin or stud 40 15 moves upwardly between the channelled portions 10 and 12 of the members 5 and 6, causing the percussion or paper-cap supported upon the head 16 to be brought into 45 exploding contact with the strike-plate of either of the devices shown and described, so that the cap will be fired with a loud report.

Of course, I am aware that some changes 55 may be made in the general arrangements and combinations of the several devices and parts, as well as in the details of the construction of the said parts, without departing from the scope of the present invention as set forth in the foregoing specification, 60 and as defined in the clauses of the claim which are appended thereto. Hence, I do not limit my present invention to the exact arrangements and combinations of the several devices and parts as described in the 65 said specification, nor do I confine myself to

the exact details of the construction of the said parts, as illustrated in the accompanying drawings.

I claim:—

1. A detonating toy comprising a rod and an exploding anvil at one end of said rod, said anvil consisting of a pair of anvil-members having inner flat face-portions and provided with oppositely located openings, the face-portions above said openings being provided with longitudinally extending channels for embracing relation of the anvil-members upon said rod, means associated with said members for permanently securing the same to the rod, the flat face-portions below said openings being also provided with longitudinally extending channels arranged to provide a guiding duct, a striking plate within the openings of said anvil-members, and a pin movably disposed within said guiding duct, said pin having an enlargement upon the end within the openings of said anvil-members. 70 75 80 85 90

2. A detonating toy comprising a rod and an exploding anvil at one end of said rod, said anvil consisting of a pair of anvil-members having inner flat face-portions and provided with oppositely located openings, the face-portions above said openings being provided with longitudinally extending channels for embracing relation of the anvil-members upon said rod, a fastening rivet extending through said members and the rod, and projections extending from within said channels into the rod for permanently securing the anvil to the rod, the flat face-portions below said openings being also provided with longitudinally extending channels arranged to provide a guiding duct, a striking plate within the openings of said anvil-members, and a pin movably disposed within said guiding duct, said pin having an enlargement upon the end within the openings of said anvil-members. 95 100 105 110

3. A detonating toy comprising a rod and an exploding anvil at one end of said rod, said anvil consisting of a pair of anvil-members having inner flat face-portions and provided with oppositely located openings, the face-portions above said openings being provided with longitudinally extending channels for embracing relation of the anvil-members upon said rod, a fastening rivet extending through said members and the rod, and projections extending from within said channels into the rod for permanently securing the anvil to the rod, the flat face-portions below said openings being also provided with longitudinally extending channels arranged to provide a guiding duct, a striking plate within the openings of said anvil-members, and a pin movably disposed within said guiding duct, said pin having an enlargement upon the end within the openings of said anvil-members, one of said anvil-mem- 115 120 125 130

bers being further provided upon its flat face-portion with lug-receiving depressions, and lugs extending from the flat face-portion of the other anvil-member in registration with said lug-receiving depressions.

4. A detonating toy comprising a rod and an exploding anvil at one end of said rod said anvil consisting of a pair of anvil-members having inner flat face-portions and provided with oppositely located openings, the face-portions above said openings being provided with longitudinally extending channels for embracing relation of the anvil-members upon said rod, means associated with said members for permanently securing the same to the rod, the flat face-portions below said openings being also provided with longitudinally extending channels arranged to provide a guiding duct, abutting members extending inwardly from the said anvil-members into the open portions thereof, said abutting members forming a striking plate, and a pin movably disposed within said guiding duct, said pin having an enlargement upon the end within the openings of said anvil-members.

5. A detonating toy comprising a rod and an exploding anvil at one end of said rod, said anvil consisting of a pair of anvil-members having inner flat face-portions and provided with oppositely located openings, the face-portions above said openings being provided with longitudinally extending channels for embracing relation of the anvil-members upon said rod, a fastening rivet extending through said members and the rod, and projections extending from within said channels into the rod for permanently securing the anvil to the rod, the flat face-portions below said openings being also provided with longitudinally extending chan-

nels arranged to provide a guiding duct, abutting members extending inwardly from the said anvil-members into the open portions thereof, said abutting members forming a striking plate, and a pin movably disposed within said guiding duct, said pin having an enlargement upon the end within the openings of said anvil-members.

6. A detonating toy comprising a rod and an exploding anvil at one end of said rod, said anvil consisting of a pair of anvil-members having inner flat face-portions and provided with oppositely located openings, the face-portions above said openings being provided with longitudinally extending channels for embracing relation of the anvil-members upon said rod, a fastening rivet extending through said members and the rod, and projections extending from within said channels into the rod for permanently securing the anvil to the rod, the flat face-portions below said openings being also provided with longitudinally extending channels arranged to provide a guiding duct, abutting members extending inwardly from the said anvil-members into the open portions thereof, said abutting members forming a striking plate, and a pin movably disposed within said guiding duct, said pin having an enlargement upon the end within the openings of said anvil-members, one of said anvil-members being further provided upon its flat face-portion with lug-receiving depressions, and lugs extending from the flat face-portion of the other anvil-member in registration with said lug-receiving depressions.

In testimony, that I claim the invention set forth above I have hereunto set my hand this 31st day of October, 1925.

MILTON M. ADLER.
